UNITED STATES PATENT OFFICE.

WILLIAM J. MONTGOMERY, OF MONTGOMERY, ALABAMA.

SURGICAL SPLINT.

Application filed March 13, 1922. Serial No. 543,311.

To all whom it may concern:

Be it known that I, WILLIAM J. MONTGOMERY, a citizen of U. S., residing at Montgomery, county of Montgomery, and 5 State of Alabama, have invented certain new and useful Improvements in Surgical Splints, of which the following is a specification.

This invention relates to splints especially 10 adapted for use in connection with broken arms, legs, shoulders, hips, etc.

Briefly stated an important object of this invention is to provide a splint consisting of a body of woven wire having longitudinal 15 and transverse members joined by means of connecting loops, the ends of which are extended outwardly to form prongs engaged by the material forming the bandage.

Other objects and advantages will be apparent during the course of the following 20 description.

In the accompanying drawing,

Figure 1 is a fragmentary side elevation of an arm equipped with the improved 25 splint;

Fig. 2 is a transverse sectional view through the splint;

Fig. 3 is a fragmentary perspective of the splint.

In the drawing, the numeral 5 generally 30 designates a frame of the improved splint, which frame is provided with longitudinal and transverse intersecting wires 6 and 7 respectively.

As illustrated in Figs. 2 and 3 the intersecting portions of the longitudinal and transverse wires 6 and 7 respectively are engaged by loops 8, the ends of which are extended outwardly to form prongs 9. The 35 prongs 9 are adapted to penetrate the material 10 forming the bandage and thereby

hold this material in place. It is thus seen that the wire loops 8 not only serve as a means to connect the longitudinal and transverse members but also as an anchoring 45 means for the bandage so that when the bandage is applied it will not be easily displaced.

Fig. 3 illustrates that the transverse wires 7 are curved longitudinally so that the 50 splint may adjust itself to the arm.

It is obvious, however, that the longitudinal and transverse wires may be curved in any desired direction to adapt itself for use in connection with various parts to be bandaged. 55

It is understood that the form of the invention herewith shown and described is to be taken merely as a preferred example of the same and that such minor changes 60 may be made as will remain within the spirit of the invention and the scope of what is claimed.

I claim:

1. A splint comprising a mesh body having longitudinal and transverse mesh forming members, and wire members having their central portions encircling the mesh forming members and their free ends projecting outwardly beyond the body on one 70 side thereof for piercing and holding a bandage wrapped about the splint. 65

2. A splint comprising a mesh body having longitudinal and transverse mesh forming members, and wire members securing the 75 mesh forming members together at their junction points and projecting beyond one face of the body for engaging and holding a bandage wrapped about the splint.

In testimony whereof I have affixed my 80 signature.

WILLIAM J. MONTGOMERY.
